RETRACTING DEVICE FOR KNEELING BENCHES

Benjamin S. Bernhard, New Britain, Conn., assignor, by mesne assignments, to Automatic Kneeler Corporation, Hartford, Conn.

Application January 16, 1946, Serial No. 641,490

9 Claims. (Cl. 155—166)

1

This invention relates to a retracting device for kneeling benches and more particularly to a device which is adapted to automatically carry a kneeling bench into an out-of-the-way position, after it has been used, and retain it in said position while not in use.

An object of the invention is to provide a device which is operated by suitable mechanism having novel advantages and which is quiet in its operation, durable in construction, and easy to operate.

Further advantages and objects of this invention will be more clearly understood from the following description and from the accompanying drawings, in which—

Figure 1 is a front view of a kneeling bench and the retracting mechanism therefor which embodies my invention.

Figure 2 is an end view, in central vertical section on line 2—2 of Fig. 1.

Figure 3 is a similar view on line 3—3 of Fig. 1.

Figure 4 is a detail view of the bumper used for my improved retracting mechanism.

Figure 5 is an enlarged front view, partially in central vertical section, of the said mechanism.

Figure 6 is an end view, in central vertical section, of a modified form of the said mechanism.

Figure 7 is a front view of the operating spring and casing therefor with the cover removed.

As shown in the drawings, 5—5 denotes the sides of a pew bench having a seat 6 extending therebetween. A kneeling bench 7 is normally positioned between the said sides 5—5, under the seat 6, and is adapted to be moved into position for use as clearly illustrated in dotted lines in Figs. 2, 3 and 6.

The mechanism for carrying said kneeling bench comprises a support that is preferably in the form of a casing 8 which is secured to one of the bench sides 5 and has a bearing 9 within which is rotatably mounted a shaft 10 that extends through a spring winding drum 11 having a notched adjusting ratchet flange 12. The said shaft is retained in position by means of a screw 13 which extends through the rear of the casing 8 and has a washer 14 fitting against a shoulder at the end of the shaft to permit rotation thereof.

A spring 15 is contained within the casing 8 with its outer end secured to an abutment 16, in the casing 8, and its inner end secured in a groove 17 in the winding drum 11.

A bench carrying lever 18 is secured to the shaft 10 and extends upwardly therefrom to a pivot 19 upon a bracket 20 that is attached to the side of the kneeling bench leg 21. Another lever 22 is

pivoted at 23, upon the casing 8, and extends therefrom to a pivot 24 upon the bracket 20.

At the opposite end of the kneeling bench 7 and attached to the leg 25 thereof there is a bracket 26 to which there is pivoted, at 27, a lever 28 which extends to a bracket 29 that is secured to the opposite bench side 5, the lever 28 being pivoted by means of a stud 30. Another lever 31 is pivoted upon the bracket 26, at 32, and extends to the pivot 33 on the bracket 29.

Suitable bumpers 34—34 are secured to the sides 5—5 in position to abut the levers 18 and 28 so as to stop the operation of the lifting device and locate the kneeling bench in its retracted position. The said bumpers may be constructed as shown in Fig. 4, and comprise a frame 35 having a tubular portion 36 within which there is mounted a spring 37 pressing outwardly on a slideable button 38 which engages one of the levers 18 or 28.

The tension on the spring 15 may be adjusted for the weight of the kneeling bench, as may be desired, by disengaging a dog 38—a, which is pivoted to the lever 18, from the ratchet 12, rotating the drum 11 until the proper tension in the spring is obtained, and then again engaging the dog 38—a with the ratchet to retain the adjustment.

The operation of the invention is as follows: In its normal position, the kneeling bench is located under the seat 6, as clearly shown in Figs. 1, 2, 3 and 6. When it is desired to use the bench, it is simply swung downwardly, to the position shown in dotted lines in Figs. 2 and 3. The parallel levers 18 and 22 and 28 and 31 will act to constantly retain the bench in a vertical position and as it is carried from the retracted position to the lowered position for use, when the movement of the lever 18 will cause winding of the spring 15.

As long as there are persons kneeling on the bench, it will remain in its downward position. When the last person arises, the spring 15 will act upon the drum 11 which in turn will rotate the lever 18 and raise the kneeling bench to its retracted position. As the bench reaches its retracted position, the levers 18 and 28 will strike the bumpers 34 and the bench will come to a stop without causing undue noise which would be rather disturbing where many of such benches would be operating at about the same time.

In order to further reduce noise from the operation of the said retracting device, I may, if desired, provide an air cushion at each side 5—5 of the seat which cushion may be in the form of

a cylinder 39 that is pivotally mounted, at 40, upon a bracket 41. A plunger 42 is pivoted by one end at 43, to a lever 18 or 28 and has a piston at the opposite end acting within the cylinder 39 to provide an air cushion for checking the upward movement of the lifting mechanism so as to raise the kneeling bench quietly and thereby eliminate disturbance or distraction to a congregation. The said air cushion also acts as a positive stop, when the plunger reaches the limit of its inward movement into the cylinder 37, to retain the kneeling bench in its retracted position.

It may be found in some cases, and particularly where long kneeling benches are used, that when the said benches are grasped for lowering from the far end opposite the spring operating side of the retracting device, there will be a twist in the bench, between that end and the opposite end, due to pull against the resistance of the spring 15 being applied from the said far end of the bench. In order to avoid this, I may provide a tie bar between the levers 18 and 28, as clearly illustrated in Figs. 1 and 5 of the drawings.

The said tie bar may consist of a tubular bar 44 and may be secured at one end to the shaft 10 by means of a connecting sleeve 45 and at the opposite end to a hub 46 upon the lever 28. This bar will tie the two opposite ends of the retracting mechanism so that they will operate together and thereby eliminate any tendency of the kneeling bench to twist regardless of where the bench is grasped for movement to its downward position.

I claim:

1. A device of the character described for lifting a kneeling bench from a lowered position to a raised position where the said bench is retracted under a seat, the said device comprising a mechanism including a casing mounted at the side of said seat, a lever pivotally mounted at one end to said casing and at the opposite end to the kneeling bench, a separate lever having one end pivoted at a point spaced from the pivot of the first lever in the casing and its opposite end pivoted to said bench at a point spaced from the first lever, spring means urging said levers to raise said bench, and stop means for limiting the movement of said layers to locate the bench in a retracted position under the seat.

2. A device of the character described for lifting a kneeling bench from a lowered position to a raised retracted position underneath a seat, the said device comprising a casing secured to one side of and under the seat, a shaft pivoted in said casing, a lever extending from said shaft and pivotally secured at its opposite end to a kneeling bench, a spring contained within said casing and having one end thereof secured to the casing and the opposite end connected to said shaft for rotating the same and urging the lever to lift the kneeling bench, and means between said spring and lever for adjusting the tension of the spring.

3. A device of the character described for lifting a kneeling bench from a lowered position to a retracted position underneath a seat; the said device comprising a casing secured to one side of the seat, a shaft rotatably mounted in said casing, a spring contained within the casing and secured thereto at one end, a spring adjusting drum rotatable in said casing and having the other end of said spring secured thereto, a ratchet portion on said drum, a lever rotatable

with said shaft and having its opposite end pivoted to a kneeling bench, a separate lever pivoted to said casing and kneeling bench parallel to the first lever, and means between the first lever and the ratchet for adjustably connecting said spring to said lever for operation of the mechanism to lift the bench from a lowered position to a retracted position.

4. A device of the character described for lifting a kneeling bench from a lowered position to a retracted position under a seat; said device comprising a mechanism having a casing mounted to one side of the seat, an axial hub in said casing, a shaft rotatably mounted in said hub, a cover for said casing, a drum projecting through said cover and rotatable upon the exterior of said hub, a spring secured between said casing and drum, a bracket having spaced pivots and secured to an end of the kneeling bench, a lever rotatable with said shaft and pivotally connected to one of the pivots on said bracket, a separate lever parallel to the first lever and pivoted to said casing and the other pivot on said bracket, adjusting means between said drum and first lever for adjustably connecting said spring to the lever for urging the said lever to raise the kneeling bench, and stop means for locating said bench in its raised position underneath said seat.

5. A device of the character described for lifting a kneeling bench as set forth in claim 4, wherein the said stop means comprises a resilient abutment engageable with the first lever to limit the movement thereof.

6. A device of the character described for lifting a kneeling bench from a lowered position to a raised retracted position under a seat; the said device comprising a casing mounted to one side of said seat, a shaft rotatable in said casing, a spring urging the rotation of said shaft in one direction, a lever rotatable with said shaft, a bracket secured to one end of the kneeling bench and having a pivotal point to which is secured one end of said lever, a second lever parallel to the first lever and pivoted to the said casing and bracket, a bracket mounted to the opposite side of said seat, a bracket secured to the opposite end of said bench, and parallel levers opposed to each of the first and second levers at the opposite end of the bench and attached to the said brackets for movably supporting one end of said bench.

7. A device of the character described for lifting a kneeling bench from a lowered position to a retracted position under a seat; the said device comprising a casing mounted at one side of said seat, a shaft rotatable in said casing, a first lever rotatable with said shaft, a second lever pivotally mounted at a point spaced from said shaft, a pair of similar levers similarly mounted at the opposite side of said seat, a kneeling bench pivotally supported upon the outer ends of said levers for movement thereof in a vertical position from a lowered to a retracted position, a spring urging said shaft for operating the first pair of levers to raise said bench, and a connecting bar rotatable with said shaft and connecting the opposite pair of levers therewith for combining the operation of said pairs of levers to wind said spring by engagement with the kneeling bench at any point thereof while preventing twisting of the kneeling bench.

8. A kneeling device of the character described for lifting a kneeling bench from a lowered position to a retracted position underneath a seat, the said device comprising a lever pivotally mount-

ed to the side of the seat and extending therefrom with its outer end pivotally secured to the end of a kneeling bench, spring means urging said lever for moving said bench from a lowered to a retracted position, means for yieldingly resisting the movement of said bench to its retracted position, said movement resisting means comprising a cylinder and a piston relatively movable and connected at one end to said seat and at the other end to the said lever to provide air pressure for resisting the retracting movement of the mechanism and stopping the kneeling bench in its retracted position when the limit of said relative movement between the piston and cylinder is reached.

9. A device of the character described for lifting a kneeling bench from a lower position to a retracted position underneath the seat, the said device comprising a casing mounted at one end of said seat, a shaft rotatable in said casing, a first lever rotatable with said shaft, a second lever pivotally mounted at a point spaced from said shaft, a pair of levers pivotally mounted at the opposite side of said seat, a kneeling bench pivotally supported upon the outer ends of said levers for movement thereof in a vertical position from a lowered to a retracted position, a spring urging said shaft for operating the first pair of levers to raise said bench, a connecting

bar rotatable with said shaft and connecting therewith the opposite lever corresponding to said first lever for combining the operation of said pairs of levers to carry said kneeling bench and prevent twisting thereof, and air pressure controlled means for yieldingly resisting the movement of the bench towards its retracted position.
